RAILWAY SWITCH OPERATING APPARATUS

George L. Temple, Rosedale Heights, Pa., assignor to The Union Switch & Signal Company, Swissvale, Pa., a corporation of Pennsylvania

Original application November 20, 1942, Serial No. 466,307, now Patent No. 2,373,517, dated April 10, 1945. Divided and this application December 9, 1944, Serial No. 567,472

3 Claims. (CL 246—291)

My invention relates to railway switch operating apparatus, and particularly to manually controlled switch operating apparatus for switches of the type which are intended to be trailed.

One object of my invention is to provide novel and improved apparatus of the type described including within a single housing manually operable means for throwing the switch to either extreme position and for subsequently yieldingly holding it in either extreme position to which it is thrown, means for locking the switch in one extreme position for facing point moves over the switch and for automatically unlocking it mechanically for trailing moves, and means for preventing objectionable slapping of the points while a train is trailing the switch.

Other objects and characteristic features of my invention will become apparent as the description proceeds.

The present application is a division of my pending application, Serial No. 466,307, filed on November 20, 1942, for Railway switch operating apparatus, now Patent No. 2,373,517, granted April 10, 1945.

I shall describe one form of railway switch operating apparatus embodying my invention, and shall then point out the novel features thereof in claims.

In the accompanying drawings, Fig. 1 is a top plan view showing a railway switch provided with one form of switch operating apparatus embodying my invention. Fig. 2 is an enlarged top view partly in section of the switch operating apparatus shown in Fig. 1. Fig. 3 is a vertical longitudinal sectional view of the apparatus shown in Fig. 2. Fig. 4 is a detail view of a portion of the apparatus shown in Figs. 2 and 3. Fig. 5 is a detail sectional view taken on the line V—V of Fig. 2. Fig. 6 is an enlarged left-hand end view of a buffering device D forming part of the apparatus illustrated in Figs. 2 and 3. Figs. 7 and 8 are vertical longitudinal sectional views of the device D shown in Fig. 6 taken on the lines VII—VII and VIII—VIII, respectively, of Fig. 6. Fig. 9 is a sectional view taken on the line IX—IX of Fig. 7.

Similar reference characters refer to similar parts in each of the several views.

Referring first to Fig. 1, the reference character A designates a railway switch comprising, as usual, two fixed rails 1 and 1a and two movable rails 2 and 2a. The fixed rails 1 and 1a are laid on tie plates 3 and are secured to crossties 4 in the usual manner. The movable rails 2 and 2a are fastened together by a front rod 5, a head

rod 6, a bridle rod 7, and a tie rod 8, and may be moved into a normal or a reverse position by means of an operating rod 9 which is connected with the head rod 6 through the medium of the usual switch basket 10. When the switch occupies its normal position in which it is shown in Fig. 1, the movable rail 2 engages the fixed rail 1, and the movable rail 2a is spaced from the fixed rail 1a. When the switch is reversed, however, the movable rail 2a then engages the fixed rail 1a, and the movable rail 2 is spaced from the fixed rail 1.

Associated with the switch A is a switch operating mechanism B embodying my invention. 15 As here shown, the mechanism B comprises a main casing 11 provided with a tail-like projection 11a, and an auxiliary casing 12 which is secured to the tail-like projection 11a of the main casing 11. The upper end of the main casing is closed by a cover 11b, while the auxiliary casing is closed by a hinged cover 12a.

A switch actuating shaft 14 is journaled in a vertical bearing 11c provided in the bottom wall of the main casing 11, and is operatively connected at its lower end with the operating rod 9 through the medium of a removable switch operating arm 14a, the parts being so proportioned that rotation of the shaft 14 through an angle of approximately 35° will move the switch between 20 its normal and reverse positions.

The upper end of the shaft 14 is provided with a two arm crank 15, the one arm of which carries a roller 16 and the other arm of which carries a roller 17 (see Fig. 4). The roller 16 extends into and cooperates with a cam slot 19a formed in a plate 19 mounted for longitudinal sliding movement in the bottom of the main casing 11, while the roller 17 extends into and cooperates with a cam slot 18a provided on the 25 underside of a plate 18 which is mounted for longitudinal sliding movement in the casing 11 directly above the plate 19. To permit the roller 17 to extend into the cam slot 18a, an opening 19b (Figs. 3 and 4) is formed in the plate 19 through which the arm of the crank 15 which carries the roller 17 extends with considerable 30 clearance. The upper plate 18 is provided on its upper side with rack teeth 120, and is adapted to be reciprocated between two extreme positions 35 by means of a hand throw lever 121 fixed to a shaft 122. The shaft 122 is journaled in suitable bearings provided in the side walls of the main casing 11, and has fixed thereto a segment gear 122a which meshes with the rack teeth 120.

A transversely extending thrust bar 124a is op-

eratively connected with the plate 119 adjacent one end thereof by means of transversely spaced bolts 125 which are secured at one end to the thrust bar and the other ends of which pass through clearance holes in an upstanding rib 119c formed integrally with the plate 119, and a similar thrust bar 124b is similarly operatively connected with the plate 119 adjacent its opposite end. The two thrust bars are biased away from the associated ribs 119c to the extent permitted by the bolts by means of compressed coil springs 126 which surround the bolts 125 between the thrust bars and the ribs, and the thrust bar 124a cooperates with a depending portion 118b formed on one end of the plate 118, while the thrust bar 124b cooperates with a depending portion 118c formed on the other end of the plate 118. The function of the thrust bars will be made clear presently.

The plate 119 is further connected at one end with the piston rod 36 of a buffing device D. This buffing device may have any preferred construction but as here shown (see Figs. 6, 7, 8 and 9) it comprises a cylinder 11f closed at one end by a cylinder head 37 and at the other end by a cylinder head 38. The piston rod 36 extends into the cylinder 11f, through a stuffing box 39, and through a suitable opening 37a in the cylinder head 37 and is fastened to two spaced reciprocable pistons 40 and 41. The cylinder 11f is intended to be filled with a suitable fluid such as oil, and the stuffing box 39 forms a fluid tight joint through which the piston rod may slide.

The wall of the cylinder 11f is provided at its left-hand end with a leak groove 100 and at its right-hand end with a leak groove 101. The function of the grooves 100 and 101 is to permit fluid to flow past the pistons under certain conditions which will be made clear hereinafter.

A reservoir 11g which may also be filled with fluid is formed in the casing 11 directly above the cylinder 11f. The cylinder is constantly connected near its center with this reservoir by means of an opening 42 in the cylinder wall. The cylinder is also connected at its left-hand end with this reservoir through two coaxial ports 43 and 44 (see Fig. 8), and at its right-hand end with the reservoir through two coaxial ports 51 and 52.

The flow of fluid through the ports 43 and 44 is controlled by a poppet valve F comprising a valve member 45 carried by a valve stem 46, and cooperating with a valve seat 43a formed in the end of the port 43. The right-hand end of the valve stem 46 is fluted and extends into the ports 43 and 44, while the left-hand end of the valve stem 46 slides in a guide bearing 47 formed in a plug 48 screwed into a threaded opening in the cylinder head 38. A spring 49 having one end located in an annular recess 50 in the plug 48 to center the spring with respect to the valve stem, engages the valve member 45 and constantly urges the valve member toward the valve seat 43a.

The flow of fluid through the ports 51 and 52 is controlled by a poppet valve G similar to the poppet valve F described hereinbefore. As here shown, the poppet valve G comprises a valve member 53 carried by a valve stem 54 and cooperating with a valve seat 52a formed in the end of the port 52. The left-hand end of the valve stem 54 is fluted and extends into the ports 51 and 52, while the right-hand end of the valve stem 54 is adapted to slide in a guide bearing 56 formed in a plug 57. The plug 57 also has formed therein an annular recess 58 which receives one

end of a coil spring 59. The other end of the coil spring 59 engages the valve member 53 and constantly urges the valve member 53 toward the valve seat 52a.

The valves F and G are operated by two tappets 60 and 61, respectively, which, in turn, are actuated by a cam 62a formed by cutting away a portion of a cam shaft 62, as best seen in Figs. 8 and 9. The tappet 60 is slidably mounted in two lugs 63 projecting upwardly from the wall of the cylinder 11f into the reservoir 11g, and the tappet 61 is likewise mounted in two similar lugs 64. The cam shaft 62 is journaled in two bearings 65 and 66 screwed into the side walls of the cylinder 11f, as best seen in Fig. 9. The outer end of the cam shaft 62 is provided with an arm 62b which is pivotally connected through an adjustable link 67 with a cam follower 141 (see Fig. 5) mounted on an eccentric cam 140 secured to the shaft 122. The parts are so proportioned that when hand throw lever 121 occupies its normal position in which it is shown in Fig. 2, the cam 62a is rotated out of engagement with the tappet 61 and into engagement with the tappet 60 so that valve G is closed and valve F is open. When the hand throw lever is rotated to its opposite extreme position, however, the cam 62a is rotated out of engagement with the tappet 60 and into engagement with the tappet 61, so that valve F is closed and valve G is open.

To facilitate the insertion of fluid into the cylinder 11f, a screw plug 69 is provided in the reservoir 11g as best seen in Fig. 9.

The cylinder 11f is further connected at its left-hand end with the reservoir 11g through a port 130, a regulating valve 131, and two ports 132 and 133, and at its right-hand end with the reservoir 11g through a port 134, a regulating valve 135, and two ports 136 and 137.

The regulating valve 131 may have any suitable form, but in the form here shown, this valve comprises a cylindrical valve member 131a fitting within a hole 138 in the cylinder head 38 and attached to a valve stem 131b. The valve member 131a is provided with a plurality of restricted orifices 131c, one or more of which may be brought into registry with the port 132 by turning the valve member 131a.

The regulating valve 135 is similar to the regulating valve 131 and comprises a cylindrical valve member 135a fitting in a hole 139 in the cylinder head 37 and attached to a valve stem 135b. The valve member 135a is provided with a plurality of restricted orifices 135c one or more of which may be brought into registry with the port 136 by turning the valve member 135a.

Reciprocably mounted in the casing 11 directly above the plate 118 is a locking device 150 comprising two spaced parallel side members 150a and 150b connected together at their opposite ends by means of integral end members 150c and 150d. The right-hand end member carries a rectangular locking plunger 80, and is formed with two spaced threaded holes 150f and 150g, while the other end member 150d is provided with three unthreaded holes 150h, 150j and 150k, two of which holes 150h and 150k align, respectively, with the threaded holes 150f and 150g. The locking plunger 80 projects with some clearance into a longitudinally extending guideway provided in a tail-like projection 111a of the casing 11, and cooperates at its right-hand end with a lock rod L which is slidably mounted in the auxiliary casing 112 at right angles to the locking plunger. The lock rod L in the form illustrated is of stand-

ard construction, and comprises two longitudinally adjustable bars 83 and 84 attached at one end to the front rod 5 of the switch A and provided with registering notches 85 so disposed that these notches will align with the locking plunger 80 when and only when the switch A occupies the extreme position in which it is shown in Fig. 1.

The locking device 150 also comprises two bolt members 150*l* and 150*m* which pass through the holes 150*h* and 150*k*, respectively, and are screwed into the threaded holes 150*f* and 150*g*. These bolt members also extend with some clearance through holes 151 and 152 formed in lugs 153 and 154 secured to the upper face of the plate 118, and surrounding each bolt member between the associated lug 153 or 154 and the end member 150*c* is a compressed coil spring 150*n* which biases the locking device in the direction to cause the locking plunger 80 to enter the notches 85 in the lock rod L.

The parts of the locking device are so proportioned that when the plate 118 is in its right-hand or normal position as shown in Figs. 2 and 3, the biasing springs 150*n* will tend to drive the locking device beyond the desired locking position. The locking device is prevented from moving beyond the desired locking position, under these conditions, however, by linkage which connects the locking device 150 with the tie rod 8. As here shown this linkage comprises a plunger bolt 155 which extends with some clearance through the hole 150*j* in the end member 150*d*, and the head of which engages the right-hand side of the end member 150*d*, as viewed in Figs. 2 and 3.

The other end of the plunger bolt 155 is adjustably connected by means of a turnbuckle 91*a* (see Fig. 1) with one end of a connecting rod 93, the opposite end of which is pivotally connected with the long arm 94*a* of a bell crank lever 94. The bell crank lever 94 is pivotally supported in a crank stand 95, and has its short arm 94*b* pivotally connected with one end of an operating rod 96. The other end of the operating rod 96 is connected with the previously described tie rod 8 by means of a standard switch basket 97. The tie rod 8 may be located at any suitable location, but will preferably be located approximately halfway between the heel and the point of the switch. The base of the crank stand 95 is secured both to a gauge plate 98 and to a tie strap 99 which is fastened at one end to the mechanism B, and it will be apparent, therefore, that any loss of adjustment between the parts due to creepage of the ties is prevented. The plunger bolt 155, turnbuckle 91*a*, connecting rod 93, bell crank lever 94, operating rod 96, switch basket 97, and tie rod 8 also constitute means for effecting the unlocking of the switch points during a trailing move, as will be made clear presently.

The operation of the apparatus as a whole is as follows: When the hand throw lever occupies the extreme position in which it is shown in the drawings, the upper plate 118 is held in its extreme right-hand or normal position, and the parts are so proportioned that under these conditions the depending portion 118*c* on the plate will engage the thrust bar 124*b* and will thereby compress the springs 126 associated with this thrust bar beyond their initial compression to thus exert a force on the plate 119 which yieldably urges it to an extreme right-hand position. The cam slot 119*a* in the plate 119 has a radius of curvature equal to the arc through which the roller 116 moves when the shaft 114 is rotated, but is disposed in the plate 119 in such an angular

position that when the plate 119 is moved to its right-hand extreme position, the roller will move to the upper end of the cam slot 119*a*, as viewed in Figs. 2 and 4 and will thus rotate the crank shaft in a clockwise direction to one extreme position. When the crank occupies this clockwise extreme position, the roller 117 on the crank 115 is disposed in the left-hand end of the cam slot 119*a*, and the parts are so proportioned that under these conditions the force applied to the crank through the cam slot 119*a* and roller 116 will yieldably hold the movable rails in their normal extreme positions. With the movable rails in their normal extreme positions, the notches 85 in the lock rod L align with the locking plunger 80, and the biasing springs 150*n* therefore move the locking device 150 to its locking position in which the plunger 80 enters the aligned notches 85 to thereby positively lock the movable rails in their normal extreme positions.

When it is desired to reverse the switch, the hand throw lever is rotated from the extreme position in which it is shown in Fig. 2 to its opposite extreme position. This movement of the lever causes the plate 118 to move from its extreme right-hand or normal position to an extreme left-hand or reverse position. As soon as the plate 118 has moved a short distance, the lugs 153 and 154 carried thereby engage the right-hand side of the end member 150*d* of the locking device 150, and as a result, as the plate 118 continues to move, the locking device 150 is moved along with the plate 118, thus withdrawing the locking plunger 80 from engagement with the notches 85 in the lock rod L, and hence unlocking the movable rails 2 and 2*a*. Furthermore, as soon as the motion plate has moved a short distance, the depending portion 118*c* will move out of engagement with the thrust bar 124*b* and will thus remove the force applied to the lower plate 119 by the associated springs 126. The parts are so proportioned that while the locking plunger 80 is being withdrawn from the notches 85 in the lock rod L, the roller 117 of the crank 115 will move along a portion of the cam slot 119*a* which is parallel to the direction of motion of the plate 118, and as long as the roller is moving along this portion of the slot, the crank 115 will remain stationary. It follows, therefore, that during that portion of the motion of the motion plate which is necessary to unlock the movable rails of the switch, no force is exerted on these rails tending to reverse them. As soon, however, as this first part of the movement of the plate 118 has been completed, the roller 117 is then engaged by a curved intermediate portion of the cam slot 119*a* which causes the crank 115 to be rotated in a counterclockwise direction, as viewed in Fig. 2, and hence causes the movable rails to be moved to their reverse positions. The counterclockwise rotation of the crank 115 also causes the roller 116 to move from the upper to the lower end of the cam slot 119*a* and hence causes plate 119 to move from its right-hand extreme position to a left-hand extreme position. During the final portion of the movement of the motion plate to its left-hand extreme position the roller 117 enters another straight portion of the cam slot 119*a* which is parallel to the direction of motion of the motion plate, and the depending portion 118*b* moves into engagement with the thrust bar 124*a* and causes the associated springs 126 to become compressed beyond their initial compression, whereby the plate 119 is yieldably urged into a left-hand or reverse extreme position. This yieldable force applied to

the plate 119 acts through the cam slot 119a and roller 116 to exert a force on the crank 115 which biases the switch points to, and yieldably holds them in, their reverse extreme positions. During the movement of the hand throw lever 121 from its normal to its reverse position the cam shaft 62 of the buffering device D is actuated to close valve F and open valve G, and during the motion of the lower plate 119 from its normal to its reverse extreme position the pistons 40 and 41 of the buffering device D are moved toward the left. Due, however, to the construction of this device, the device offers substantially no resistance to the movement of the plate 119 under these conditions. It should be noted that as long as the movable rails remain stationary, the plunger bolt 155 remains fixed, so that during the first part of the movement of the motion plate the end member 150d of the locking device 150 will move out of engagement with the head of the plunger bolt. As soon as the movable rails have started to move, however, the resultant movement of the tie rod 8 acting through the linkage which connects the plunger bolt with the tie rod causes the plunger bolt to move in the same direction that the motion plate is moving although the time of motion and rate of motion will bear no direct relation to the movement of the motion plate.

When the movable rails have been moved to their reverse positions in the manner just described, they may be restored to their normal positions by restoring the hand throw lever 121 to the position shown. The subsequent movements of the parts under these conditions are just the reverse of those described above, and it is believed that the operation of the apparatus under these conditions will be readily understood from an inspection of the drawings without further description.

I shall now assume that the parts are in their normal positions, as shown in the drawings, and that a train trails the switch. As the leading wheels of the train roll along the fixed rail 1 and the movable rail 2a, the movable rails 2 and 2a are forced over laterally, but before a sufficient force is developed to overcome the force which yieldably holds the points of the movable rails in their normal positions, the movable rails will become bent intermediate their ends and this bending will act through the linkage connecting the tie rod 8 with the locking device to move the locking device 150 in opposition to the bias of the springs 150n a sufficient amount to withdraw the locking plunger 89 completely out of engagement with the notches 85 in the lock rod L, thus unlocking the switch. As a result, when the leading wheels have reached the positions in which sufficient force is developed to overcome the force holding the points of the movable rails in their normal positions, the movable rails will be unlocked, with the result that the rails will be forced toward their reverse positions by the wheels in exactly the same manner as if no point lock were provided. The movement of the rails toward their reverse positions will rotate the crank 115 in a counterclockwise direction, as viewed in Fig. 2, and this rotation will act through the roller 116 and cam slot 119a to force the plate 119 toward the left. The motion of the plate 119 toward the left, in turn, will compress the springs 126 associated with the thrust bar 124b beyond their initial compression so that these springs will exert an increased force tending to return the movable rails toward their normal extreme positions. The motion of the plate

119 toward the left will also force the piston rod 136 into the buffering device D. Due to its connection with shaft 122, the camshaft 62 will remain stationary under these conditions and will hold the valve F open and the valve G closed. As a result, the buffering device will offer very little resistance to the movement of the piston rod into the cylinder, but any movement of the piston rod in the opposite direction will be limited to the relatively slow rate at which fluid can flow through the valve 135. It will be seen, therefore, that the buffering device will act to prevent the movable rails from snapping back to their normal positions between the passage of successive pairs of wheels through them. When the train which is trailing the switch has completely passed the switch, the movable rails will slowly return to their normal positions under the bias of the springs 126 associated with the thrust bar 124b, and against the retarding force of the buffering device D. During this return movement of the movable rails there will be no deflections of these rails, and the locking plunger 89 will be moved into engagement with the lock rod L before the movable rails have reached their full normal positions in which the lock rod is in the proper position for the notches 85 in the lock rod L to receive the locking plunger. The springs 150n will therefore become compressed, and will urge the locking plunger into engagement with the side of the lock rod, until the notches 85 move into alignment with the locking plunger, at which time the energy stored in the compressed springs 150n will force the locking plunger into place in the notches, thus restoring the switch to its normal locked condition.

The apparatus shown in Figs. 2 and 3 is intended to be provided with a circuit controller disposed in the auxiliary housing 112 for indicating when the switch occupies its normal position and is properly locked in this position. This circuit controller is not shown since it is of well known construction. It is intended, however, to be mounted in the auxiliary casing 112, and may, for example, be similar to that shown and described in Letters Patent of the United States No. 1,976,827, granted to Herbert L. Bone on October 16, 1934, for Railway switch operating apparatus.

If a train trails the switch when the switch is reversed, the switch will be unlocked and will remain unlocked, but otherwise the operation of the apparatus will be similar to that just described.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

1. In combination with a railway switch, a switch actuating shaft rotatable between two extreme positions and operatively connected with said switch for moving said switch between its two extreme positions, a first plate manually reciprocable between two extreme positions, a second plate reciprocable between two extreme positions and operatively connected with said first plate through spring means, cam means formed in said two plates respectively, a crank secured to said shaft and provided with two rollers one cooperating with the cam means in each said plate, said cam means being so arranged that said spring means will act to bias said switch

to one extreme position or the other according as said first plate is moved to its one or its other extreme position and that when said first plate occupies either extreme position said crank is free to rotate in opposition to said spring means.

2. In combination with a railway switch, a switch actuating shaft rotatable between two extreme positions and operatively connected with said switch for moving said switch between its two extreme positions, a first plate manually reciprocable between two extreme positions, a second plate reciprocable between two extreme positions and operatively connected with said first plate through spring means, cam means formed in said two plates respectively, a crank secured to said shaft and provided with two rollers one cooperating with the cam means in each said plate, said cam means being so arranged that said spring means will act to bias said switch to one extreme position or the other according as said first plate is moved to its one or its other extreme position and that when said first plate occupies either extreme position said crank is free to rotate in opposition to said spring means, locking means for locking said switch in one extreme position, means connected with said first plate for biasing said locking means to a locking position when said first plate is moved to one extreme position and for moving said locking means to an unlocking position when said first plate is moved to its other extreme position, and means mechanically actuated by a train trailing said switch for moving said locking means to its unlocking position.

3. In combination with a railway switch, a switch actuating shaft rotatable between two

extreme positions and operatively connected with said switch for moving said switch between its two extreme positions, a first plate manually reciprocable between two extreme positions, a second plate reciprocable between two extreme positions and operatively connected with said first plate through spring means, cam means formed in said two plates respectively, a crank secured to said shaft and provided with two rollers one cooperating with the cam means in each said plate, said cam means being so arranged that said spring means will act to bias said switch to one extreme position or the other according as said first plate is moved to its one or its other extreme position and that when said first plate occupies either extreme position said crank is free to rotate in opposition to said spring means, locking means for locking said switch in one extreme position, means connected with said first plate for biasing said locking means to a locking position when said first plate is moved to one extreme position and for moving said locking means to an unlocking position when said first plate is moved to its other extreme position, means mechanically actuated by a train trailing said switch for moving said locking means to its unlocking position, a buffering device operatively connected with said second plate and effective when a train trails said switch to oppose movement of the switch by said spring means, and means for rendering said buffering device ineffective to oppose movement of said switch when said first plate is manually reciprocated between its two extreme positions.

GEORGE L. TEMPLE.
